UNITED STATES PATENT OFFICE.

HARRY N. DRUCKER, OF CINCINNATI, OHIO.

TRUNK-LOCK.

No. 918,662.

Specification of Letters Patent.

Patented April 20, 1909.

Application filed September 18, 1908. Serial No. 453,642.

To all whom it may concern:

Be it known that I, HARRY N. DRUCKER, a citizen of the United States of America, and resident of Cincinnati, county of Hamilton, 5 State of Ohio, have invented certain new and useful Improvements in Trunk-Locks, of which the following is a specification.

The object of my invention is a means of locking the side, the top and the bottom of 10 the door of a trunk, which means consists of a minimum number of simply constructed parts, whose operation is positive and easy.

My invention relates especially to wardrobe trunks.

15 Referring to the accompanying drawings forming a part of this specification: Figure 1 is a perspective view of a section of a wardrobe trunk, showing the door or flap thereof provided with a latch embodying my invention. Fig. 2 is an inside elevation of the door and latch, upon an enlarged scale, the door being shown broken out and the parts being brought together to economize space. Fig. 3 is a detail elevation of the case with the top 20 plate removed, to expose the movable bars. Fig. 4 is a view similar to Fig. 3 showing the parts in a different position. Fig. 5 is a detail sectional view taken upon line $x-x$ of Fig. 3 upon a much enlarged scale.

30 Referring to the parts: The inside door, A, of the trunk section is hinged in the usual way at, a , a' , and has adjacent to its opposite side a rectangular perforation. The housing of the latch consists of a plate, B, which 35 registers with the rectangular perforation in the door, has flanges, b and b' , at its top and bottom and a flange, b^2 , at its front side, all of which flanges project into the rectangular perforation in the door. From flange, b , lugs, 40 b^3 and b^4 , are struck outward and a lug, b^5 , is struck inward leaving a space between the lug, b^5 , and the plate, B. Flange, b' , has similar outwardly projecting lugs, b^6 and b^7 , and a similar inwardly projecting lug, b^8 . 45 The lugs, b^3 , b' , b^6 , and b^7 , receive screws for holding the plate, B, to the door, A.

The top of the housing is formed by a plate, C, which has a central elliptical hole with an inwardly turned flange, c . Plate, C, 50 is placed against the external face of the door, A. Within the housing formed by the flanged plate, B, and the flat plate, C, is located a reciprocating plate, D, which has formed integrally with it a forwardly projecting bar, d . Plate, D, has two converging slots, d' and d^2 , and has struck up from it a

finger piece, d^3 , which projects into the elliptical opening in plate, C. The slots, d' and d^2 , are engaged by pins, e and e' , respectively which project inward from vertical bars, E 60 and E'.

Plate, D, is situated between lugs, b^5 and b^8 , and the plate, B, and is of a length less than the length of the housing. The forward movement of the plate carries the bars 65 E, E' to a position such that their outer ends project beyond the edges of the door, A, so as to engage keepers in the sides of the trunk section. These keepers are of ordinary construction and are not shown. Bars, 70 d , E, and E', have guides, d^6 , e^2 , and e^3 , respectively near their outer ends. Plate B, has a projection, b^9 , struck inward from it, which when the plate, D, is in its forward position engages an indentation, d^4 , which is 75 struck into the end of the plate, D.

The operation of the latch on the inside of the cover is as follows: After the door has been closed, as shown in Fig. 1, the finger piece, d^3 , is moved to the left, which carries 80 the bar, d , into its keeper, and causes the walls of the slots, d' and d^2 , to carry the bars, E and E', outward into their keepers, and causing the projection, b^9 , by reason of the spring in the metal of the plate, B, to take 85 into the indentation, d^4 , which holds the bars in their locked position. When it is desired to unlock the door the simple movement of the finger piece, d^3 , toward the right withdraws the bar, d , from its keeper, and draws 90 the bars, E and E', likewise inward out of engagement with their keepers.

What I claim is:

1. The combination of a trunk door having a perforation in it, a housing seated within 95 the perforation, a plate adapted to slide within the housing, a bar secured to the plate projecting through the front of the housing upon the rear face of the door and adapted to be moved toward and from its keeper by the 100 reciprocation of the plate, bars projecting through opposite sides of the housing upon the rear face of the door, inclined sliding connection within the housing and between the plate and the latter bars and adapted to 105 move the bars toward and from their keepers upon the reciprocation of the plate, and a finger piece secured to the plate and projecting outward to the front face of the door for reciprocating the plate.

2. The combination of a trunk-door, a 110 housing secured to the door, a plate having

converging slots in it and adapted to be reciprocated longitudinally in the housing, a bar projecting through the end of the housing and secured to the plate, and bars projecting 5 through the sides of the housing and having pins engaging the slots in the plate.

3. In a trunk lock the combination of a housing whose bottom consists of a metal plate having an inward projection, lock bars 10 adapted to be reciprocated toward and from

the housing, a metal plate within the housing adapted to reciprocate in ways adjacent to the bottom of the housing for actuating the bars and an indentation in the plate to fit into the projection in the housing and to clamp 15 the plate in the locked position of the bars.

HARRY N. DRUCKER.
